UNITED STATES PATENT OFFICE.

WILLIAM A. JENNINGS, OF RAYTOWN, MISSOURI.

CYLINDER-HONING TOOL.

Application filed October 12, 1925. Serial No. 62,009.

This invention relates to cylinder honing and polishing tools of that class in which cylinder engaging elements, such as hones, are held against the interior wall of the cylinder at diametrically opposite points and revolved while in such position, such elements being pivotally supported so that they may assume positions parallel to the wall, the case being a continuation in part of application filed by me March 10, 1924, Serial No. 698,184.

In all devices heretofore, of the general character outlined, the honing or equivalent elements have been disposed for adjustment 15 on a single line radially diametric of the cylinder and in consequence have been capable under certain conditions, of rocking or tilting and hence producing a bevel or flare at the end of the cylinder as they emerge 20 therefrom sufficiently to bring their pivotal points beyond the corresponding end of the cylinder, because as heretofore constructed, no provision has been made to lock the hones or the like against pivotal action when 25 bearing wholly below their pivotal points, against the cylinders.

I have found that to guard against the possibility of such rocking or tilting of the hones under the conditions named, it is essential to lock them against pivotal movement, and one of my objects therefore is to provide means for applying a pressure or 30 reactional resistance laterally on the hones which exceeds or preponderates over the force tending to impart pivotal movement 35 to the hones.

Another object is to produce a construction by which it is possible to expand or collapse the tool while in grinding or polishing operation, and either before or after it is disposed within a cylinder to be ground or polished.

Another object is to provide hone-carrying holders in overlapping relation and bearing sidewise against each other so that each will oppose any tendency of the other to spring or bend laterally, that is, rearwardly with respect to the direction of rotation.

With these general objects in view, the invention consists in certain novel and useful features of construction and combinations of parts as hereinafter described and claimed; and in order that it may be fully

understood, reference is to be had to the accompanying drawing, in which:

Figure 1 is a view partly in side elevation and partly in central vertical section, of a tool embodying the invention, and also shows a cylinder in central vertical section, 60 and in engagement with said tool.

Figure 2 is an elevational edge view of the tool, with a part broken away to disclose features of construction otherwise hidden.

Figure 3 is an inverted horizontal sectional view taken on the line III—III of Figure 1.

Figure 4 is a detail perspective view of one of the hone holders of the tool.

Referring to the drawing in detail, 1 indicates a cylinder to be internally ground and polished, the cylinder being preferably immovably supported in any suitable manner. Arranged within the cylinder, when in operative position, is a pair of elements which are adapted to perform the grinding and polishing operation or either of such operations, said elements extending longitudinally of the cylinder and when in operation in parallel relation thereto. They also stand at opposite sides of the axis of the cylinder and, when in flat or slab like form as shown, are adapted to engage the wall of the cylinder at diametrically opposite points. With respect to the direction of rotation, as indicated by arrows in Figure 3, the front outer corners of the two hones or the like are shown as engaged with the wall of the cylinder.

The hones are pivotally mounted as at 3 so as to be capable of rocking edgewise and thereby accommodate themselves to the wall of the cylinder so that their outer edges shall parallel and engage the cylinder wall.

A pair of holders comprise front arms 4 and rear and preferably larger arms 5, the arms being connected at their inner edges by cross pieces 6, so that each holder in plan view, is approximately U-shaped. The rear or inner arms 5 of the holders are preferably straight and contact with each other in the plane of the axis of the cylinder, and mounted in said arms are the pivot bolts 3 hereinbefore mentioned, for the cylinder-engaging elements 2, the heads of the bolts being counter-sunk in said arms. Preferably the said elements have double flaring or

spool-shaped metallic cores 7 as bearings for said pivot bolts, and the front ends of said cores are provided with recesses 8 containing springs 9 which bear against the cores 5 and the smaller or front arms 4 of the holders for the purpose of crowding the honing elements 2 or the like flatly against the arms 5 of the holders to maintain said arms 5 and said elements in frictional relation at all 10 times. This insures a more instantaneous locking of the elements 2 against pivotal operation after said elements, when in rapid rotation, are rocked to parallel relation—if not parallel with the cylinder,—by the resistance offered by the latter, as hereinafter more clearly appears.

The arms 5 of the holders are provided near their upper ends with lugs 10 for a purpose which hereinafter appears, and the 20 flatwise abutting arms 5 engage a central bifurcation 11 in a head or member 12, which in the preferred form of construction is adapted to be rapidly rotated. The said head is also provided at opposite sides of 25 bifurcation 11 with a pair of bifurcations 13 for receiving the upper ends of arms 4, which arms preferably are bent inward near their upper extremities to avoid the necessity of using a member 12 of undue diameter, 30 and a pivot pin 14 carried by member 12, forms a pivotal support for the holders.

The head 12 is formed with a reduced portion 15, and is screwed upon the end of a driving shaft 16. A sleeve 17 fits upon the 35 head and is threaded on portion 15 thereof, and at its lower end is provided with an annular angle flange 18 for fitting upon and around the lugs 10 of the holders, downward adjustment of the sleeve on the head 40 causing the former to apply pressure on lugs 10 for swinging the holders outwardly in opposite directions to expand the tool and bring the hones or the like, into contact with the wall of the cylinder. This expanding 45 movement of the tool is limited by the depending or enclosing portion of said flange 18, and contracting or collapsing movement will be limited by engagement of said lugs 10 with the head 12, it being apparent by 50 reference to Figure 1 that slight inward or outward movement of the lugs 10 is accompanied by a relatively large or extended swinging movement of the hones or the like so that the appliance is capable of use in 55 cylinders of materially different diameters, though in practice motor cylinders for use upon which the tool is primarily designed, rarely exceed an inner diameter of approximately three and three-fourths inches.

60 Assuming that the tool, in collapsed condition, has been positioned with the hones wholly within a cylinder and to the far end thereof from the driving shaft, the rotatable movement is started through any suitable 65 control or clutch (not shown), and the oper-

ator grips the sleeve lightly so that if it rotates at all it will rotate at a materially retarded speed. This difference in the speed of rotation between the head and the sleeve causes the latter to move toward the holders, 70 and by applying pressure on the lugs 10, expand the tool. If the honing elements are initially tilted either way with respect to the cylinder, they will, under the resistance offered thereby, instantly rock to the parallel position described so that for their full length they shall engage the cylinder. As this is accomplished the sleeve is released and the full length contact of the hones with the cylinder wall presses the hones—with respect to the direction of rotation—rearwardly against the large arms 5 of the holders and develops a friction between the hones and said arms so great it exceeds that of the edgewise grinding pressure of the hones on the cylinder. In the actual operation there will be a conventional relative longitudinal feeding movement effected by hand or otherwise of the hones with respect to the cylinder 80 so that the former shall gradually grind the cylinder from one end to the other and thus insure uniformity of diameter for its full length.

In the event that the operator through inattention or otherwise, should fail to arrest the grinding operation by the time the pivotal points 3 of the hones attain a position exterior to the end of the cylinder from which the hones emerge, it will be impossible for the hones to swing pivotally outward at 90 their upper ends and thus produce a flare or bevel in the cylinder, and this is due to the fact that at all times the large arms 5 offer a frictional resistance to pivotal movement of the hones which is in excess of the edgewise pressure on the cylinder which tends to impart such pivotal movement to the hones, this relatively great pressure of the hones on the holders for locking the former, being due primarily to the fact that the 100 hones are disposed in planes which bear chordal relations with the circle of rotation of the operating element or head. It will be obvious if the hones both stand to swing in the plane of the axis of the cylinder, that the pivotal action would occur because the resistance of the cylinder to edgewise pressure of the hones would be greater than any lateral pressure which could be applied by the hones on the holders. In effect the 110 action of the hones on the cylinder is a wiping action, as will be noted particularly by reference to Figure 3, tending to press the hones with greater force laterally than inwardly.

115 It will be apparent that as the tool remains in expanded condition until the sleeve is reversely adjusted to permit of inward or collapsing movement of the holders by 120 gravitational action, the continued operation 130

of the driving member, causes the hones by light contact with the cylinder wall to perform a polishing or smoothing function, it being understood however, that purely polishing members of less abrasive material, such as pumice stone or even felt, may be substituted for the grinding members, if desired.

From the above description, it will be apparent that I have produced a device of the character described which possesses all of the features of advantage set forth as desirable, and while I have described and claimed the preferred embodiment of the same, I reserve the right to make all changes properly falling within the spirit and scope of the appended claims.

What I claim is:

1. A tool for grinding and polishing concave cylindrical surfaces, comprising a rotary driving member, a pair of holders pivotally carried by the driving member, and fitting flatly together in overlapping relation in the plane of the axis of said member, elements carried respectively by said holders for operation in parallel planes chordal to the circle of operation of the driving member and the surfaces to be ground or polished, and means for effecting simultaneous

outward swinging movement of said holders to dispose the said elements in engagement with the surfaces to be ground or polished.

2. A tool for grinding and polishing concave surfaces, comprising a rotary driving member, a pair of holders pivotally carried by the driving member and bearing an overlapping relation to each other, and elements carried respectively by said holders for operation in parallel planes chordal to the circle of operation of the driving member and to the surfaces to be ground or polished.

3. A tool for grinding and polishing concave surfaces, comprising a rotary driving member, a pair of holders pivotally carried by the driving member and bearing an overlapping relation, and elements carried respectively by said holders and pivoted thereto, each of said holders on the back side of its respective element as regards the direction of rotation being of such area that the frictional force between such parts of the holder and the element is greater than the force tending to rock the element around its pivotal point in the holder.

In witness whereof I hereunto affix my signature.

WILLIAM A. JENNINGS.
